Application March 10, 1942, Serial No. 434,102

6 Claims. (Cl. 235—61.9)

This invention relates to accounting machines and more particularly to the type in which result recording is effected under control of a final result accumulator and wherein the result is changed by a "rounding off" operation.

In bookkeeping systems, it is sometimes desirable to accept the tens order of a final result derived by a computing machine as one digit higher when the digital value of the lower or units order is 5 to 9. This, in the art, is known as "rounding off" operations. Previously it was the practice to effect a rounding off operation by causing the lower order accumulator wheel to receive the entry of "5" and through the usual carry operation the next accumulator wheel would be augmented by 1 if the lower order wheel represented either 5 to 9. This, however, required an additional cycle of machine operation and lengthened the time to get the rounded off result.

The main object of the present invention is to provide for rounding off operations independently of accumulator operation and without requiring an additional operation of the machine. To this end, the improvement is applied to a readout of a well known construction in which is incorporated a rounding off device, whereby the digital setting of the higher order section of the readout will be augmented by the digital value of one unit when the readout section of the lower order represents any of the digits 5 to 9.

More specifically the object is attained by providing for each lower order a supplemental readout section which detects whether the lower order represents 0-4 or 5-9. In accordance with such digit representations there is a selection of one of two additional readout sections of next higher order, one section having normal wiring for reading out the original indicated digit when the lower order is 0-4, and the other section wired differently so as to read out the next higher digit when the lower order represents 5-9.

It is a still further object of the invention to provide these additional readout sections for each lower order and next higher order of the readout and to additionally include a selective arrangement whereby rounding off operations may be effected for any of the higher orders of the readout.

A still further object of the invention is to provide for the automatic recording of zeros for one or more of the lower orders which consist of the orders in which rounding off operations are not effected. Thereby the order which is rounded off will represent either the original indicated digit

or the next higher digit and the lower orders and will be recorded by one or more zeros. This will enable the recording of the final result in the manner desirable and suitable for some accounting systems.

- 5 A still further object of the invention is to enable rounding off operations to be effected for orders still higher than the selected order when the selected order represents 9 and is to be augmented by a unit. This resembles somewhat carry operations in an accumulator and is incorporated in the present arrangement so as to provide proper recording of rounded off figures irrespective of the original digit representation.
- 10 15 While the readout shown herein is preferably set in accordance with the digit representation of a final result accumulator, it is obvious that the readout may represent an item which may be required to be rounded off and therefore the disclosure of a readout controlled by an accumulator
- 20 should be considered as merely illustrative and not restrictive. Furthermore, the type of recording mechanism controlled by the readout is also immaterial. Since the readout may control a
- 25 printing mechanism but furthermore may be utilized as the controlling element for a punching recording mechanism, the coordination of two different types of recording mechanism with the improved readout illustrates very clearly that the
- 30 invention is not restricted to its coordination with any specific type of recording mechanisms and various other types may be utilized with similar advantages and benefits.

Other objects of the invention will be pointed out in the following description and claims and illustrated in the accompanying drawings, which disclose, by way of example, the principle of the invention and the best mode, which has been contemplated, of applying that principle.

40 In the drawings:

Fig. 1 is a schematic layout of the drive from several of the illustrative accumulator elements to the brush readout sections.

Fig. 2 is a fragmentary sectional view showing the construction and arrangement of the drive for some of the readout sections.

Fig. 3 illustrates a conventional form of printing mechanism which may be coordinated with the present readout.

50 Fig. 4 is a wiring diagram showing the wiring of the improved readout and its coordination with the print selecting magnets of the printing mechanism shown in Fig. 3.

Fig. 5 is a view similar to Fig. 4 but shows the wiring when the improved readout is to be coordi-

nated for control of a punching mechanism of a well known type.

The construction of the result readout device is similar to that shown in the patent to G. F. Daly, 2,045,437, dated June 23, 1936, for the MPRO readout shown in Fig. 12, the construction shown therein being modified for adaptation to the present invention. The electrical connections for the readout are shown in Figs. 4 and 5 whereas Fig. 1 shows the driving gear connections for three illustrative orders.

In Fig. 1, 240 represents the clutch gear pertaining to the units order of the result accumulator and corresponds to the accumulator clutch element which is driven differentially to represent the digit of the entry. Gear 241 of the readout is driven from this clutch gear and gear 241 in turn drives a brush assembly designated 242u which traverses the complete series of digit representing segments 243 and a common current supply segment 244. Elements 242u, 243 and 244 represent the customary elements of each section of a readout device. Like the construction shown in Patent No. 2,045,437, the lower section of the readout, which has just been described, is provided with an associated and concurrently driven upper section and the brush assembly of the upper section of the units order is driven as follows: A gear 252 is driven from the gear 241 which in turn drives the gear 253 which positions a single brush assembly 254u. The brush 254u traverses a complete series of digit representing segments 257 as well as a current supply segment 258. It will, therefore, be noted that the units or lowest order of the result readout consists of two concurrently driven sections. These segments are wired as shown in Fig. 4 and will be subsequently described in detail.

The tens, hundreds and thousands order sections are all similar in construction and Fig. 1 represents the driving connections for each of these orders, it being described, particularly in connection with the tens order. The tens order clutch wheel 242 positions four concurrently driven brush assemblies, two being provided in the lower driven section and two in the upper driven section. The tens order clutch wheel 248 drives a gear 238 which drives a brush assembly 245t and this brush assembly contacts with a common current supply segment 249 and only the 9 digit representing segment, it being noted that for this section (as well as for corresponding sections of higher orders) the other digit representing segments are omitted. (See also Fig. 4.) A gear 233 is driven from the gear 239 which in turn drives a gear 237 and by such gear 237 a brush assembly 254t is driven which cooperates with a common current supply segment 259 and a series of digit representing segments 227. Also by the gear 237 a brush assembly 236t is driven and this cooperates with a complete series of digit representing segments 235 and a common current supply segment 234. Also, in the lower section the gear 239 drives a brush assembly 242t cooperating with a complete series of digit representing segments 239 and a common current supply segment 251.

The highest order of the result readout device of the present invention, and which herein consists of the tens of thousands order, comprises only three sections. The accumulator clutch gear pertaining to the highest order is represented by the numeral 233 which drives a brush 232th through a series of idler gears 231. The brush

232th is provided with a common current supply segment 230 but the brush 232th cooperates only with the 9 digit representing segment, the others being omitted for this brush assembly. The idler gear 231 which is directly driven by the clutch gear 233 drives a brush assembly 229th which cooperates with a series of digit representing segments 220 and also a common current supply segment 228. The idler gear which drives brush assembly 232th also drives a brush assembly 221th which cooperates with digit representing segments 223 and a common current supply segment 222. Therefore, the highest order of the result readout consists of one lower driven section and two upper driven sections.

Recording mechanism

It may be well at this time to understand that the improved readout device is adapted to control any suitable type of recording mechanism and at this time the arrangement shown in Fig. 3 will be described in order to better understand how the readout of the digital values in the readout device can be interpreted in printing a result on a result sheet. As will be later described, instead of printing the values punching mechanism may also be utilized.

The printing mechanism shown in Fig. 3 is of a well known construction and is used in tabulating machines for printing both items and totals and in the present case it would obviously be used for recording the total results.

Shaft 25 designates the usual total printing shaft which rotates a cam 26. Cam 26, through the lever 27, causes a crosshead 28 to be raised and lowered under the action of cam 26. A plurality of type bars 29 are spring connected to the crosshead 28 and as the crosshead is raised, and lowered, the type bars are operated the same way. As each type bar is raised, the ratchet teeth 35 thereof pass a pawl 34. At the time that the type 30 of a type bar approaches the printing position in front of the conventional platen 31, a circuit is completed to a printing selecting magnet 32 which attracts its armature 33, releasing the stop pawl 34 and causing the pawl to engage the proper tooth 35 of the type bar, thus stopping any further movement of the type bar 30. When the type bars are at the printing position, hammers 36 are operated to print from the type upon a sheet surrounding the platen 31. As the crosshead 28 is lowered, the type bars are positively restored to their home position. It is understood that a type bar selecting magnet 32 is provided for each denominational order and these are shown in the electrical diagram in Fig. 4, it being noted that suitable plug connections 41 are made between the plug sockets 42 connected to the print selecting magnets 32 and the plug sockets 40 pertaining to the successive denominational orders of the readout. The denominational orders of the plug sockets 40 increase from right to left, this being also true of the denominational orders of the printing selecting magnets 32.

Rounding off device—rounding off operations for units order

In multiplying or dividing it is sometimes desirable to record the result amount to the nearest tens, hundreds, thousands digit, etc., which operation is known in the art as "rounding off." For example, if the computation results should be 40 to 44, in accounting practice this will be accepted as a round figure, namely 40; whereas if

the computation result should terminate in the digits 5 to 9 in the units order, this should be recorded as one higher in the tens order. Thus, if the computation result should be 45 to 49, the result would be rounded off to the next higher tens digit and recorded as -50-. At present there will now be described the operations which take place when the rounding off operation is effected for the tens order, being determined by the units order.

To accomplish this a plug wire connection 44 is made between the plug socket 43 and the plug socket 45a for the tens order and when the switch SW closes, a circuit will be completed from the line 48 through the switch SW, plug socket 43, plug connection 44, plug socket 45a, and thence through the relay coil A to the line 49, thereby energizing relay A and the latter will transfer its contacts A2, A3, and A5, A6. Other contacts controlled by the relay A will also be transferred but these will be ineffective for the present example.

Referring to the wiring diagram (Fig. 4), an emitter 46 of a well known construction is illustrated and comprises a current supply segment, a brush 47, and a series of commutator elements having suitable connections to the digit lines 50, there being ten digit lines, one for each of the digits 0 to 9, inclusive. The emitter has a wire connection from the current supply segment to the line side 48 and through the various sections of the readout selected impulses are directed to the printing selecting magnets 32. At this point it might be well to state that the brush assembly 47 of emitter 46 makes one-half revolution for each complete revolution of shaft 25. The impulses are thereby transmitted from the emitter through the readout to energize magnets 32 at times which are in synchronous relationship with the presentation of the type to the printing position.

It will be assumed that the final computation result represents a value from 40 to 44 and the rounding off operation should cause the recording of this amount as -40-. It will be noted that the tens recording control circuit is made by the plug connection to the plug socket 40t and the tens circuit extends from this plug socket through the relay contacts B3, which are now closed, to the current supply segment 258 which is engaged by the brush 254u and which latter may be at any of the digit representing positions 0-9 but at 4 in the assumed example. It will be noted that the segments 257 engaged by the brush 254u are divided into two separate groups, 0 to 4 and 5 to 9 and the segments 0 to 4 are interconnected and by a wire 51 are connected to the current supply segment 234 associated with the tens order brush 236t which is positioned to engage the 4 segment of the associated series 235. The other group of segments of the group 257 representing 5 to 9 are interconnected by a wire 52 and when the tens order is selected for rounding off the circuit extends through the contacts A6 to the current supply segment 259 of a readout section of the tens order. The segment 259 is contacted by the brush 254t which latter engages the series of digit segments 227. It will be noted that the group of digit segments 235 representing the same digit are connected to the digit lines 50 bearing the same digital value but the set of digit representing segments 227 are wired so that they are connected to the next higher digit lines. Therefore, when the units order represents 0 to 4, the tens order will be recorded as the same digit 70

but whenever the units order represents 5 to 9, the tens order will be recorded as one higher than the original digit. In either case, the first readout section of the units order will be ineffective for recording due to the fact that the energization of the A relay has closed the A2 contacts and connected the units recording control circuit at the plug socket 40u to the zero digit impulse line.

In order to make a clearer reference to the particular sections of the readout which are involved in the description of operation, it will be noted that beneath each section there is a numeral enclosed by a circle and this numeral identifies the particular numbered readout section which will be referred to in the description. The units order consists of sections 1 and 2; the tens order consists of sections 3, 4, 5 and 6, the hundreds 7-10, etc.

Therefore, in rounding out the tens order, it will be noted that section 1 of the dual section of the units order will be ineffective, due to the opening of contacts A3 and closure of A2 contacts, and furthermore, whether section 3 or section 4 of the tens order will be effective for the readout of the digital value will be dependent upon the brush setting of brush 254u of section 2 of the units order. If readout section 2 of the units order represents 0 to 4, section 4 will be selected for operation but if section 2 of the units order represents either 5 to 9, section 3 of the tens order will be selected for operation.

It is also understood that if rounding off operations are not to be effected, there will be a normal reading of the result on the readout in all orders, due to the normal closure of contacts A3, B3, C3, and D3. It will be noted that for the units order, the controlling section would be section 1. For the tens circuit, the circuit would be through the B3 contacts and irrespective of whether the units order represents 0 to 4 or 5 to 9, it will be noted that section 4 of the tens order will always be the controlling section for the tens order, due to the opening of contacts A6 and the wiring connection 51 from the group of units digit segments 0 to 4 to section 4, and for the group of digit segments 5 to 9 of the units order the tens circuit extends through contacts A5 now closed to section 4. The closure of contacts A5 and opening of contacts A6 renders section 3 ineffective to change digit recording for the tens order when the digit is 5-9.

A somewhat similar circuit connection can be traced for the hundreds, thousands, and tens of thousands order.

Selective operation of rounding off device for orders above the units order

The previous description was confined to the operation of the rounding off device when the latter is utilized for rounding off digital values for the tens order in accordance with the digit values of the units order. It is desirable at times to effect the operation of the rounding off device for still higher orders. That is, rounding off operations above the tens order for the present readout would be effected for the hundreds, thousands and tens of thousands order, thereby determining the digital values read out for these orders in accordance with the digital values of the next lower order.

To this end, a series of relays designated B, C, and D are provided with suitable plug socket connections so that by an appropriate plug connection 44 the rounding off operation may be effected for the selected order. When the plug

connection is made to plug socket 45b, the relay B will be energized which will close its contacts B1, thereby energizing the relay A. These relays are energized for rounding off operations for the hundreds order, and in accordance with the digital value of the next lower or tens order, the digital value will be either increased in the hundreds order or read out as the original indicated digit.

This rounding off operation is desirable when values such as 400 to 440, 500-540, 700-740, etc., are to be recorded as 400, 500, 700, whereas values ranging from 450 to 490, 550-590, 750-790 are to be recorded as a rounded off figure or 500, 600, 800. It will be noted that in the result recorded, 400 or 500, for example, the original units and tens digits are disregarded and recorded as zeros. The energization of the relays A and B will close their respective contacts A2 and B2 which will connect the units and tens order recording control circuits to the "0" digit line 50, invariably recording zeros for these two orders when the hundreds order is to be rounded off. For the hundreds order control circuit which terminates at the plug socket 40h, it will be noted that the normal closure of contacts C3 will connect this circuit to the segment of readout section 5 of the tens order which is the type of readout section previously described in that it can discriminate between the digit positions 0 to 4 and 5 to 9. When the brush 242t for the tens order is at the digit positions 0 to 4, it will be noted that readout section 8 is selected for operation so that the normal digit representation of the hundreds order will be recorded. However, if 5 to 9 should be represented in the tens order, the hundreds order circuit will be closed from the brush 242t through the 5 to 9 digit segments of readout section 5, through contacts B3 now closed to readout section 7 of the hundreds order. This is the type of readout section previously described in that its digit representing segments are connected to the digit lines 50 one digit higher. Hence, if the tens order represents 5 to 9, the hundreds order will be augmented in its digit representation by a units digit.

Rounding off operations for thousands and tens of thousands order

The selective operation for the rounding off device for the hundreds order is effected by making the plug connection 44 to the plug socket 45b, whereas for the thousands order, the plug connection is made to the plug socket 45c. When the relay coil C is energized, the relay coils B and A will also be energized, whereas when the D coil is energized by the selective plug connection to plug socket 45d for rounding off in the tens of thousands order the other coils C, B and A will be energized. In each case, it will be noted that in accordance with the coils energized, the A2, B2, C2 and D2 contacts will be closed so that when the plug sockets 40u to 40th are the lower orders of the particular order to be rounded off, each of these entry control circuits will be connected to the zero digit impulse line 50. When the relay coil C is energized for rounding off operations in the thousands order, it will be noted that the closure of contacts C5 will cause the segments 5 to 9 of readout section 9 of the hundreds order to cause a circuit to be closed through contacts C6 to select readout section 11 of the thousands order. Since relay contacts D3 are normally closed in rounding off the thousands order, the digit rep-

resenting segments 0 to 4 of readout section 9 will select readout section 12 of the thousands order for recording.

Likewise, when the tens of thousands order, which is the extreme order at the left, is to be rounded off, the relay coil D will be energized and by the closure of contacts D6, readout section 13 of the thousands order will select readout section 15 of the tens of thousands order for augmenting the tens of thousands order by 1 if the digit representing brush in the thousands order represents a value from 5 to 9. From the plug socket 40th for the tens of thousands order control circuit, it will be noted that the control circuit is directly connected to the current supply segment of readout section 13 and if the related brush of this readout section represents 0 to 4, the readout section 16 of the tens of thousands order is selected for digit recording. In this case, the original digital value of the tens of thousands order will be recorded and all lower orders will be recorded as zeros.

Summarizing:

1. If the order lower than the order selected for rounding off represents the digits 0-4, this order is unchanged and the original digital representation thereon is recorded.
2. If the order lower than the order selected for rounding off represents the digits 5-9, the digit representation of this order is augmented by a unit in recording.
3. All orders which may be one or more below the order selected for rounding off should be recorded as "0" irrespective of the recording made for the order selected for rounding off.

Rounding off operations utilizing "9" carry

In the previously described examples the description of rounding off operations involving "9" carry was avoided but these operations must be provided for when the selected order to be rounded off ends in "9" and should be augmented by "1," due to the lower order representing 5-9. This control is effected for the tens, hundreds, and thousands order by the supplemental readout sections numbered 6, 10, and 14, a similar type of readout section 11 being provided for a special purpose in the tens of thousands order.

When the tens order is selected for rounding off, relay A is energized to close contacts A4 and if such order represents "9" the readout section 6 will have its brush standing at the "9" digit segments, causing a circuit to be closed from line 48, through switch SW, contact A4, through the current supply segment 249, related brush 245t, and "9" digit segment of readout section 6 to relay E, to line 49. Relay E energizes and closes contacts E2, and opens contacts E1. The opening of contacts E1 will open the hundreds recording control circuit at this point, the normal circuit being from plug socket 40h, contacts C3, readout 5 at the "9" digit position, through contacts B1, E1 to readout section 8 to thus prevent recording of the original indicated digit in the hundreds order. The closure of contacts E2 will cause this circuit to be made from contacts B7 through contacts E2 to readout section 7, which is the type of readout section to augment by "1" the original indicated digit. Obviously, if the tens order stands at "9," the hundreds entry control circuit will be from plug socket 40h, through contacts C3, readout section 5 at "9" digit position, contacts B7, contacts E2, to readout section 1. Hence, whatever the original digital value in the hundreds order, this will be increased by a unit.

In the above example a recording of "0" will be made for the tens order because readout section 3 was selected for recording by the 5-9 segments of section 2 and since brush 254t is at "9" in readout section 3, a zero will be recorded because of the wiring to the "0" impulse line.

A numerical condition is also met where succeeding higher orders are at "9." For example: -9995-; and since it was explained how the hundreds order was recorded as "1" for a rounded off number such as -95-, it will be observed that if the hundreds order is at "9," readout section 10 will represent "9." With readout section 6 at "9," relay E will be energized and by the wire connection 53, the energizing circuit is extended through readout section 10 to relay F to energize the latter. Hence, the thousands order control circuit will be through relay contacts D3, readout section 9 at "9," relay contacts C5, relay contacts F2 to readout section 11 which also being at "9" will be read out as "0." The readout section 14, in a similar manner, will cause relay G to be energized and if the tens of thousands order is at any digit position but "9," readout section 14 will select readout section 15 for recording, augmenting the digit representation therein by a unit.

Summarizing:

1. If in the selected order to be rounded off the digit is "9," and the next lower order position is at 5-9, the selected order must be read out as zero and the next higher order one unit higher.

2. If in the selected order to be rounded off the digit and all orders above are "9" and the lowest order digit is 5-9, all of these orders must be read out as zero and the order carried to must be recorded by a unit higher.

Preferably, if the readout should represent -99995-, the digit representing capacity of the illustrative readout, the rounded off result should be recorded as -100000- and is effected as follows: Relays E, F, G are energized as described, and readout section 14 will continue the energizing circuit to readout section 17 which, being at "9," will cause relay H to energize, and close its H2 contacts. Hence, the recording control circuit for the hundreds of thousands order at plug socket 40h will extend by wire 54 through relay contacts H2, and by a wire 55 to the "1" digit impulse wire 50. Thus, the highest order of the recording mechanism will record "1."

It should also be noted that the particular order where carry operations are started and incidental zero recording for lower orders is determined by the particular relays A, B, C, or D energized. If rounding off should be selected for the hundreds order, relay B is energized; and B1 contacts are opened, thus opening the "9" transfer circuit through B1 contacts and E2 contacts to readout section 1 even if the tens order should be at "9." However, the "9" carry can be effected for higher orders including the hundreds order if such orders are at "9."

In the same manner relays C and D disable, by the opening of their contacts C5 and D5, the carry circuits from the hundreds and thousands orders when rounding off should be instituted at the thousands and tens of thousands order.

Alternative form of result recording mechanism

The operation of the improved readout device has been described in connection with the recording mechanism of the type shown in Fig. 3 wherein concurrent result recording operations may be performed. The improved readout may

also be used as the recording control means for a recording mechanism of the successive recording type and, for example, may comprise the type of punching machine shown in the patent to F. L. Lee et al. No. 1,976,618, dated October 9, 1934.

The electrical wiring connections from the readout to the coordinated elements of the punching machine are shown in Fig. 5, it being noted that for the impulse emitter 46 a series of punch control magnets 57 are in circuit connection with the digit lines 50. These magnets correspond to the punch selecting magnets designated 60 in the aforementioned patent. It will be understood, therefore, that as the successive orders of the readout are read out, the punch selecting magnets 57 will be selected for energization to effect the punching of the card to represent the digits corresponding to the rounded off result amount. In each order where an increment of unit is to be made, the punch selecting magnet 57 of the next higher digit will be selected for operation.

In the upper left hand corner of Fig. 5 there is shown a step-by-step column readout device designated generally by reference numeral 56. This type of column readout is well known in the art and is shown in a number of prior patents, among these being the patent to Daly 2,016,706, dated October 3, 1935. As a general description of the operation of this column readout device, as the card carriage is stepped along the contact 56 is moved therewith to successively establish the recording control circuits, thereby causing the readout sections to select the punch selecting magnets to punch the card order by order.

While there has been shown and described and pointed out the fundamental novel features of the invention shown in the preferred embodiment, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. A readout device for rounding off digits in a higher order according to digit representations in a lower order comprising a series of digit lines, a higher order circuit, a lower order readout section comprising a pair of digit representing segments, one at digit representing positions 0-4 and the other at 5-9 and an element settable on either of said segments according to the lower order digit representation, a dual section higher order readout comprising two settable elements and two sets of digit representing segments, one set being connected to the digit lines of the same digital value, and the other set connected to digit lines of the next higher digit, said digit segment 0-4 of the lower order and the related settable element when at any of the 0-4 digit positions completing a circuit from the higher order circuit to the settable element in contact with the set of segments of the higher order which are connected to digit lines of the same digital value, and the digit segment 5-9 of the lower order and the related settable element when at any of the 5-9 digit positions completing a circuit connection from the higher order circuit to the settable element in contact with the set of segments of the higher order which

are connected to the digit lines of the next higher digit.

2. A readout device for rounding off digits in a higher order according to digit representations in a lower order comprising a series of digit lines, a higher order recording circuit, a series of digit recording control elements connected to corresponding digit lines, a lower order readout section comprising a pair of digit representing segments, one at digit representing positions 0-4 and the other at 5-9 and an element settable on either of said segments according to the lower order digit representation, a dual section higher order readout comprising two settable elements and two sets of digit representing segments, one set being connected to the digit lines of the same digital value, and the other set connected to digit lines of the next higher digit, said digit segment 0-4 of the lower order and the related settable element when at any of the 0-4 digit positions providing a circuit connection from the higher order recording circuit to the settable element engaging the set of segments of higher order which are connected through said digit lines to digit recording control elements of the same digital value, and the digit segment 5-9 of the lower order and the related settable element when at any of the digit positions 5-9 providing a circuit connection from the higher order recording circuit to the settable element engaging the set of segments of the higher order which are connected through said digit lines to the digit recording control elements of the next higher digit.

3. A readout device for rounding off digits in a higher order according to digit representations in a lower order comprising a series of digit lines, a units order circuit, a tens order circuit, a units order readout section comprising a pair of digit representing segments, one at digit representing positions 0-4 and the other at 5-9 and a settable element in circuit connection with the tens order circuit settable on either of said segments according to the units order digit representation, a dual section tens order readout comprising two settable elements and two sets of digit representing segments, one set being connected to the digit lines of the same digital value, and the other set connected to digit lines of the next higher digit, the settable element of the units order providing when at any of the 0-4 digit positions a circuit connection from the tens order circuit to the settable element engaging the set of segments of the tens order which are connected to digit lines of the same digital value, and the settable element of the units order when at any of the 5-9 digit positions providing a circuit connection from the tens order circuit to the settable element engaging the set of segments of the tens order which are connected to digit lines of the next higher digit, selectively operated means, and means controlled by the selectively operable means for connecting the units order circuit to the "0" digit line and for enabling the aforementioned circuit connections from the tens order circuit to be completed under control of the settable element of the units order according to its digit position 0-4 or 5-9.

4. A readout device for selectively rounding off digits in one of a plurality of higher hundreds or tens orders according to digit representations in the next lower tens or units order respectively, comprising a series of digit lines, a units order circuit, a tens order circuit, a hundreds order circuit, a readout section for the units and tens circuit,

order, each comprising a pair of segments, one at digit representing positions 0-4 and the other at 5-9 and a settable element in circuit connection with the next higher order circuit and settable on either of said segments according to the related order digit representation, a dual section tens and hundreds order readout comprising for each order two settable elements and two sets of digit representing segments, one set being connected to the digit lines of the same digital value, and the other set connected to digit lines of the next higher digit, the 0-4 segment of the units or tens order and the related settable element when at any of the digit positions 0-4 providing circuit connections from the next higher or tens or hundreds circuit respectively, to the settable element engaging the related set of segments of the tens or hundreds order which are connected to digit lines of the same digital value, the 5-9 segment of the units or tens order and the related settable element when at any of the digit positions 5-9 providing circuit connections from the next higher or tens or hundreds order circuit respectively, to the settable element engaging the related set of segments of the tens or hundreds order which are connected to digit lines of the next higher digit, means selectively operable when rounding off is to be effected in the tens order, means controlled by said means for enabling circuit connections to be completed under control of the settable means of the units order according to its digit positions 0-4, 5-9, other means selectively operable when rounding off is to be effected in the hundreds order, and means controlled by said last named means to open the circuit connection between the settable element of the units order and the tens order circuit and for enabling circuit connections to be completed for the hundreds order circuit under control of the settable means of the tens order according to its digit positions 0-4, 5-9.

5. A readout device for selectively rounding off digits in a higher order beyond the units order comprising a set of digit recording control elements, a subdivided supplemental digit representing means for the units order and each higher order in which a digit is to be rounded off for detecting by its digit representation whether the related order represents 0-4 or 5-9, a dual section readout for each higher order exclusive of the units order, each section comprising a settable means and a set of segments, the segments of one section having wiring connections to digit recording control elements of the same digital value and the settable means thereof having a circuit connection to the digit representing means of the subdivision of the readout of next lower order representing 0-4, and the segments of the other readout section having wiring connections to digit recording control elements of the next higher digit value, and the settable means thereof, having a circuit connection to the digit representing means of the other subdivision of next lower order representing 5-9, a plurality of selectively operable control means one for each order in which a digit rounding off operation is to be effected, and means controlled by each of said control means for causing the related subdivided supplemental digit representing means to have the aforesaid circuit connections completed to one readout of the dual section of next higher order or the other readout thereof dependent upon the digit representation of the subdivided digit representing means

next lower in order, and for rendering ineffective the subdivided supplemental digit representing means in all orders below that in which the subdivided digit representing means are effective to control rounding off operations.

6. A machine according to claim 4 which further includes devices to connect the units order circuit to the "0" digit line, and supplemental devices to connect the tens order circuit to the

"0" digit line, and wherein the means which is selectively operable when rounding off is effected in the tens order causes the operation of the first named devices, and the means which is selectively operable when rounding off is to be effected in the hundreds order causes the operation of both of said devices.

JOHN N. WHEELER.
